ATTORNEY

UNITED STATES PATENT OFFICE.

CHARLES C. MEEKER, OF NEWARK, NEW JERSEY, ASSIGNOR OF ONE-HALF
TO THE BLESS & DRAKE, OF SAME PLACE.

SAD-IRON.

SPECIFICATION forming part of Letters Patent No. 592,808, dated November 2, 1897.

Application filed May 19, 1897. Serial No. 637,171. (No model.)

To all whom it may concern:

Be it known that I, CHARLES C. MEEKER, a citizen of the United States, and a resident of Newark, in the county of Essex and State of New Jersey, have invented certain new and useful Improvements in Sad-Irons, of which the following is a specification.

The invention relates to improvements in sad-irons; and it consists in the novel features of construction hereinafter described, and particularly pointed out in the claim.

The invention pertains particularly to sad-irons in which the handle is detachable from the body of the iron and is provided with a spring-latch mechanism by which it may be applied to the body of the iron whenever desired, and said invention is confined especially to the novel construction of the body of the iron hereinafter pointed out.

20 The object of the invention is to improve and render more durable and useful the body of the iron and to lessen the expense of manufacturing said body.

In accordance with my invention the entire body of the iron is in one integral piece of cast metal ready to receive the detachable handle and to be securely held thereby.

The body of the iron constructed in accordance with my invention has at its center a cavity extending downward below the upper surface of the iron and traversed by a bar integral with the iron, this cavity and bar being more particularly described hereinafter. The upper surface of the body of the iron is provided with ribs or lugs to guide the handle-plate and with bearing-surfaces for said handle-plate, all being integral with the body of the iron.

40 The invention will be more fully understood from the detailed description hereinafter presented, reference being had to the accompanying drawings, in which—

Figure 1 is a top view of the body of a sad-iron constructed in accordance with and embodying the invention. Fig. 2 is a central longitudinal section of same on the dotted line 2 2 of Fig. 1, the handle being in position upon the body of the iron; and Fig. 3 is a central vertical transverse section through the body of the iron on the dotted line 3 3 of Fig. 1.

In the drawings, A designates the body of the iron, and B the handle therefor, said handle being of usual construction and comprising the handle-plate C, wooden holder D, pivoted spring-latch E, and toe F. The toe F is an integral part of the plate C, and the latch E is acted upon by the usual spring G, fastened to said plate C. The handle B forms no part of the invention sought to be protected hereby and is of well-known form and construction.

The body A is cast complete in one integral piece and has upon its upper surface the guiding ribs or flanges H and bearing-surfaces I, 65 the flanges H serving to retain and guide the side edges of the handle-plate C and the surfaces I receiving the lower surface of said handle-plate C. At the center of the upper portion of the body A is formed the cavity J, 70 which is substantially elliptical in horizontal outline and is encompassed by the walls K, which incline downward and outward, thus leaving the upper end of the entrance to the cavity smaller than the lower end or base of 75 the cavity. The walls K incline downward and outward correspondingly entirely around the cavity J, as indicated by the full lines in Fig. 2 and by the dotted lines in Fig. 1. The depth of the cavity J will be sufficient to receive the toe F and engaging end of the spring-latch E, as indicated in Fig. 2.

The cavity J is traversed at its upper end or entrance by the transverse bar L, which has a rounded lower surface, as illustrated in 85 Fig. 2, and is integral with the body A. The ends of the bar L curve outward, as indicated at a, to merge into the outline of the upper end of the cavity J, as indicated in Fig. 1, whereby said bar L at its ends where they 90 merge into the body of the iron are rendered broad and strong and capable of withstanding the usage to which sad-irons are subjected.

The ends of the bar L below the upper surface of said bar curve downward and outward 95 to merge into the vertical walls K of the cavity J, as indicated more clearly in Fig. 3 at b b. The lower surface of the bar L at its ends thus has a form which will tend to center the toe F of the handle-plate C, and the bar L at its ends is given an increased thickness in a vertical direction, whereby said bar

is rendered more durable and more capable of withstanding the strains to which it will be subjected in use. The ends of the bar L thus, as above described, are broadened across 5 their upper surface, as indicated at *a* in Fig. 1, and are thickened on vertical lines, as indicated at *b* in Fig. 3, and said bar L is thus rendered entirely durable and lasting. The 10 fact that the walls K incline downward and outward aids in securing the greater thickness in a vertical direction of the ends of the bar L and results in a material increase in the strength of said bar L. The form of the 15 cavity K and the merging surfaces of the inclined walls K and bar L all combine to adapt the iron to receive the handle B and guide the toe F therein into proper relation to the cross-bar L.

As above described, the body A is in one 20 integral piece, the cavity J, cross-bar L, guiding-ribs H, and bearing-surfaces I being all formed at one casting operation.

In addition to the advantages above pointed out due to the present invention it may 25 be said that the integral cross-bar L furnishes a means by which the body A may be securely held during the grinding and polishing of the bottom and sides of the iron and that in view

of the bar L being confined to the center of the body A the sides of the said body may be 30 polished entirely up to their upper edges in the most satisfactory manner.

What I claim as my invention, and desire to secure by Letters Patent, is—

For detachable-handle sad-irons, the body 35 A in one integral cast piece and having at its center the cavity J and cross-bar L, said cavity having the downwardly and outwardly inclined walls K, and said cross-bar being integral with said body and uniting therewith 40 on the curved lines *a*, *b*, the latter extending downward and outward to merge into the lower portion of said outwardly-inclined walls K, whereby the outer ends of said cross-bar are thickened in vertical direction and the 45 lower surfaces of said outer ends at their extremities are carried outward beyond the ends of the upper surfaces of said cross-bar; substantially as and for the purposes set forth.

Signed at Newark, in the county of Essex 50 and State of New Jersey, this 11th day of May, A. D. 1897.

CHARLES C. MEEKER.
